UNITED STATES PATENT OFFICE.

GUSTAV REINHOLD PESTER, OF WITTGENSDORF, NEAR CHEMNITZ, GERMANY.

PROCESS OF PRODUCING MELANGE-LIKE DYED YARNS, HOSIERY, AND WEAVINGS.

1,145,846.

Specification of Letters Patent.

Patented July 6, 1915.

No Drawing.

Application filed January 9, 1915. Serial No. 1,464.

To all whom it may concern:

Be it known that I, GUSTAV REINHOLD PESTER, a subject of the German Emperor, and resident of Wittgensdorf, near Chemnitz, Kingdom of Saxony, German Empire, have invented certain new and useful Improvements in Processes of Producing Melange-like Dyed Yarns, Hosiery, and Weavings, whereof the following is a specification.

It is known that out of loose wool and cotton yarn may be spun and such yarn dyed in different colors. The product thereby obtained is called "melange." It is also known that differently dyed threads may be twined together and that the yarn thereby obtained is called "jaspe."

According to the present invention two different threads, for example, undyed wool and undyed cotton, preferably four or many-fold, are twined together in a raw state and then dyed (for example in a bath of a wool dye). By this process an effect is obtained which neither presents the undistinct feature of the "melange" nor that of the "jaspe," but produces quite a new and special impression, a color-effect lying between that of the two aforesaid methods.

The product obtained by the new process which might perhaps be termed "jaspe-melange," shows sharper and more regular outlines than the "melange," but, on the other hand, it presents when compared with the real "jaspe," a more melange-like character.

In putting this process into operation, I may twist together one or more fine yarns of undyed cotton, and one or more threads of undyed wool to produce a simple thread. After which two or more of these simple threads are twisted together to produce a compound thread (four fold or manyfold). This treatment of threads is referred to in the textile art as twining. This is not to be confused with a known process in which two or more wool yarns are twisted together to produce a wool thread, and this wool thread twisted with a similar thread of cotton material, nor is it to be con-

fused with a known process in which 50 yarns are made from a mixture of wool and cotton, which are twisted together to produce compound threads. This thread is now dyed, as for example with wool blue, whereby the wool will be thoroughly dyed 55 blue, while the cotton takes only a very light shade of color. The dyed thread may thereafter be dyed, for example in chamois, whereby the cotton becomes thoroughly dyed, whereas the wool, previously dyed 60 blue, will take only a little shading.

By this process the effects of the two colors will influence each other in such a manner that beautiful transition-colors, not obtainable in any other way, will result 65 therefrom and produce superior "melange" effects.

Of course the most different colors may be combined by this system, so as to produce the most varying melange-shades. It is 70 quite astonishing to see how completely dyed threads show in many cases effects as if not only two but even three, four or more shades have been combined in the thread.

What I claim is:—

75

1. The herein described process of producing jaspe-melange textiles, which comprises the steps of twisting together a plurality of yarns of different undyed materials having different dye absorbing properties, 80 twisting together a plurality of the threads thereby obtained in order to produce twined thread of at least four fold, and dyeing the final thread in a bath of a dye having different actions on the different constituents 85 of the thread, substantially as set forth.

2. The herein described process of producing a jaspe-melange textile, which comprises the steps of twisting together a plurality of yarns of undyed cotton and undyed 90 wool, twisting together a plurality of the threads thereby produced, in order to produce a thread of at least four fold, and dyeing the final thread in a bath of a wool dye, substantially as described.

95

3. The herein described process of producing jaspe-melange textiles, which comprises the steps of twisting together yarns

of wool and yarns of cotton, to produce a thread, twisting together a plurality of threads obtained in this manner, dyeing the thread thereby produced in a bath of a wool dye, and thereafter dyeing the same in a bath of a cotton dye, substantially as set forth.

Copies of this patent may be obtained for five cents each, by addressing the "Commissioner of Patents, Washington, D. C"

In testimony whereof I have set my hand under this specification in the presence of two subscribing witnesses.

GUSTAV REINHOLD PESTER.
